Primary Examiner — Michael A Maharajh(74) *Attorney, Agent, or Firm* — Pierce Atwood LLP;
Kevin M. Farrell(57) **CLAIM**

The ornamental design for a stimulation device, as shown and described.

DESCRIPTION

FIG. 1 is a front perspective view of a stimulation device showing our new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is the top plan view thereof; and,

FIG. 7 is the bottom plan view thereof.

The broken lines in the drawings depict portions of the stimulation device that form no part of the claimed design.

1 Claim, 4 Drawing Sheets(56)
